EXCAVATING MACHINE

Robert Andrew Denovan, Asbestos, Quebec,
Canada

Application December 26, 1935, Serial No. 56,257

8 Claims. (Cl. 37—116)

This invention relates to excavating machines and more particularly to a machine for digging trenches and the like wherein the excavating means is carried by a boom laterally offset from the power machine.

5 An object is to provide a simple arrangement wherein a tractor may be readily mounted on the machine and dismounted therefrom in order to provide transporting means for the machine.

10 A further object is the provision of a simple and inexpensive arrangement for deriving power from the tractor for moving the machine and operating the excavating means.

15 The invention contemplates the provision of an excavator, including a supporting deck, wherein a boom is offset with respect to the deck whereby the machine may be positioned on solid ground adjacent the portion to be excavated with the boom extending over said portion 20 in such a manner as to provide greater convenience and efficiency of operation. The invention also includes cable means for operating an excavating bucket in association with the boom and for swinging the boom about a vertical axis, the cable means being driven from a single shaft, which in turn is driven by power supplied by the tractor. It also includes means for propelling the machine along the line of work.

25 30 The invention will now be described with reference to the accompanying drawings, in which

Figure 1 is a side elevation with certain parts removed for clarity of illustration,

Figure 2 is an end elevation,

35 Figure 3 is a plan view, and

Figure 4 is a sectional view showing tractor mounting.

In the drawings, 1 represents a supporting deck for the machine mounted on wheels 2, 3 is 40 a boom, 4 a bucket of usual construction connected to the boom 3 and 5 a tractor mounted on deck 1 and having its rear driving wheels 6 jacked up by means of jacks 7 for furnishing the motive power for the machine.

45 The boom is pivotally secured at its lower end to a fitting 8 carried by a turntable 9 pivotally mounted at the base of a mast 10 which is mounted in an offset position with respect to deck 1, on a projecting end of a horizontal beam 11 carried by and extending transversely across deck 1, and its upper end is tied by means of a cable 12 to a casting 12' pivotally mounted at the top of mast 10.

50 55 The mast 10 is supported by a pair of trans-

verse rigid stays 13 secured to beam 11 and to a bracket 14 adjacent the top of the mast, and by upper and lower back stays 15 anchored to the deck.

An outrigger 16 having a hinged connection 5 with the bracket 14 is adapted to prevent any overturning movement of the machine due to the offset position of the boom.

The driving mechanism of the machine includes a jack shaft 17 journaled in bearings 18 10 mounted on frame members 19 and 20 and driven by means of chains 21, sprockets 22 bolted to the drive wheels 6 of the tractor and corresponding sprockets 23 mounted on the jack shaft. A drum shaft 24, journaled in bearings 25 mounted 15 on a frame member 26 and frame member 19, respectively, is driven by a chain 27 and sprockets 28 carried by the drum shaft and the jack shaft. A loading drum 29 and a hoisting drum 30 are mounted on the shaft 24 for driving connection therewith by means of clutches 31 and 32 provided with operating levers 31' and 32', respectively. Any suitable braking means may be provided for each of drums 29 and 30 and operating levers therefor are indicated at 29' and 30'. A pair of bevel gears 33 are also mounted on shaft 24 for driving connection therewith by means of clutches 34 provided with an operating lever 34' and are in meshing engagement with a bevel gear 35 keyed 30 to a short vertical shaft 36 mounted on deck 1. A swing drum 37 is also keyed to shaft 36 and suitable braking means therefor may be provided, a brake operating lever being indicated at 37'. 35

Swinging of the boom is effected by means of a cable connection 38 between the drum 37 and turntable 9.

>Loading of bucket 4 is effected by means of a cable 39 coiled on drum 29 and extending through a horizontally positioned sheave 40 at the side of deck 1, thence through a second horizontal sheave 41 mounted in a block adjacent the foot of mast 10 and over a vertical sheave 42 mounted in a block carried by turntable 9 to a connection on bucket 4, as shown.

Hoisting of the bucket is accomplished by means of a cable 43 coiled on drum 30 and extending through a sheave 44 carried by a block 50 loosely mounted on bracket 14 at the top of mast 10, thence through a sheave 45 mounted at the end of boom 3 to a connection on the bucket.

Means, for propelling the machine along the line of work, include a cable 46 coiled on a drum

47 mounted on an extension of jack shaft 17 journalled in a transverse frame member 48. The drum 47 is mounted for driving connection with shaft 17 by means of a clutch 49 provided 5 with an operating lever 50. The free end of cable 46 is led through a vertical sheave 51 mounted between the frame members 20 and 48, thence through a horizontal sheave 52 mounted on frame member 48 and through a sheave 53, 10 which is tied by a cable 54 to any suitable anchor, to a connection on a hand steering device 55.

The operation of the machine will be apparent from the foregoing description. The machine may be placed on solid ground adjacent the line 15 of the trench to be excavated, as indicated at 56, with the boom extending over the trench in advantageous operating position. The outrigger 16 extends to the opposite side of the trench for supporting purposes. The shafts 17 and 24 are 20 driven by the tractor and loading, hoisting, swinging and propelling of the machine are accomplished by operating the various clutches to drive the respective drums and set in motion the actuating cables.

25 I claim:

1. A tractor-driven excavating machine comprising a supporting deck therefor, a boom carried by but offset with respect to the deck, a bucket connected to the boom, loading and hoisting means for the bucket including a pair of coaxially mounted drums and actuating cables associated therewith, means for swinging said boom about a vertical axis including a drum and an actuating cable associated therewith, said last- 30 mentioned drum having an axis at right angles to the axis of said first-mentioned drums, a common driving shaft adapted to impart rotation to each of said drums and a second shaft adapted to be driven by the tractor and having a driving 35 connection with said first mentioned shaft.

2. In a tractor-driven excavating machine including a supporting deck therefor, a boom and a bucket, loading and hoisting means for the bucket comprising a driven shaft, a pair of drums 45 mounted on said shaft, clutches associated with said shaft and drums, and actuating cables operatively connecting said drums and bucket, and driving means for said driven shaft comprising a pair of sprockets bolted to the rear driving 50 wheels of the tractor, chain driving means connecting said sprockets to a second shaft and additional chain driving means connecting said second shaft to the driven shaft.

3. A tractor-driven excavating machine as defined in claim 2, wherein means is provided for swinging said boom about a vertical axis, said means comprising a mast, a fitting rotatably mounted on the mast and to which the boom is secured and means for rotating the fitting consisting of a turntable to which the fitting is secured, a drum mounted on a shaft at right angles to said driven shaft and adapted to be rotated thereby and a cable connecting the turntable and last-mentioned drum.

65 4. A tractor-driven excavating machine as defined in claim 2, wherein said boom is carried by but offset to said deck.

5. In a tractor-driven excavating machine in-

cluding a supporting deck therefor, a boom mounted in an offset position with respect to the deck substantially over the line of work of the machine, and mounting means for said boom comprising a laterally extending beam carried by 5 the deck, a mast mounted on the extended end of said beam, a fitting rotatably mounted at the base of said mast and pivotally carrying said boom and an outrigger secured to the top of said mast and extending across the line of work to 10 prevent overturning movement of the machine due to the offset position of the boom.

6. In a tractor-driven excavating machine including a supporting deck therefor, a boom mounted in an offset position with respect to 15 the deck substantially over the line of work of the machine, mounting means for said boom comprising a laterally extending beam carried by the deck, a mast mounted on the extended end of said beam, a turntable rotatably mounted at the base of said mast, a fitting secured to said turntable and pivotally carrying the boom, and an outrigger secured to the top of said mast and extending across the line of work to prevent 20 overturning movement of the machine due to the offset position of the boom, and means for swinging said boom about the axis of said mast including a drum mounted about a vertical axis on the deck, an actuating cable connecting the drum and turntable and means for rotating 25 the drum.

7. In a tractor-driven excavating machine including a supporting deck therefor, a boom and a bucket, said boom being mounted in an offset position with respect to the deck substantially 30 over the line of work of the machine, mounting means for said boom comprising a laterally extending beam carried by the deck, a mast mounted on the extended end of said beam, a turntable rotatably mounted at the base of 35 said mast, a fitting secured to the turntable and pivotally carrying the boom, and an outrigger secured to the top of the mast and extending across the line of work to prevent overturning movement of the machine due to the offset position of the boom, means for swinging the boom about the axis of said mast including a drum mounted on the deck and an actuating cable 40 connecting the drum and turntable, and loading and hoisting means for the bucket including a pair of coaxially mounted drums and loading and hoisting cables leading from said coaxially mounted drums to the bucket, said turntable having a sheave fixed thereto through which passes the loading cable, said mast having a 45 sheave pivotally secured to the top thereof through which passes the hoisting cable.

8. A tractor-driven excavating machine as defined in claim 2, wherein means is provided for propelling said machine along its line of work, 50 said means comprising a drum mounted coaxially of said second shaft, a clutch adapted to effect driving engagement between said second shaft and last mentioned drum, anchor means for the machine, and an actuating cable leading 55 from said anchor means to said last mentioned drum.

ROBERT ANDREW DENOVAN.
